INVENTOR:

August H. Opperman,
BY
E. T. Silvius,
ATTORNEY.

UNITED STATES PATENT OFFICE.

AUGUST HENRY OPPERMANN, OF INDIANAPOLIS, INDIANA.

ELECTRICAL CURLING-IRON HEATER.

Application filed September 16, 1922. Serial No. 588,546.

To all whom it may concern:

Be it known that I, August H. Opperman, a citizen of Germany, residing at Indianapolis, in the county of Marion and 5 State of Indiana, have invented a new and useful Electrical Curling-Iron Heater, of which the following is a specification, reference being had to the accompanying drawings and to the letters and figures of 10 reference marked thereon.

This invention relates to an electrical heater of the type that is hollow or oven-like in which curling irons or other articles may be moderately heated, the invention 15 having reference in particular to a portable heater that may be placed and used where most convenient.

An object of the invention is to provide a heater which shall be so constructed as to 20 permit it to be safely used where most convenient, as upon furniture in apartments without danger of injuring the furniture.

Another object is to provide an improved 25 electrical heater which shall be of simple and inexpensive construction and be adapted for heating various articles either within the heater or on the outside thereof, and which shall be durable and economical in use.

With the above-mentioned and other objects in view, the invention consists in an 30 improved portable electrical heater including an improved oven, of such construction as to be adapted to be readily repaired if necessary; and, the invention consists also 35 further in the novel parts and in the combination and arrangement of parts as hereinafter particularly described and further set forth in the appended claims.

Referring to the drawing,—Figure 1 is a 40 side elevation of the improved heater as preferably constructed; Fig. 2 is a vertical central sectional elevation of the heater on an enlarged scale; and, Fig. 3 is a transverse 45 section on the line III—III in Fig. 2.

In the several figures of the drawings corresponding or like reference characters indicate corresponding parts or features of construction herein referred to in detail.

As preferably constructed the improved 50 heater comprises a slab-like base 1 which may be composed of wood or other suitable material and preferably is oblong in plan. The bottom of the base preferably is provided 55 with a suitable pad 2 composed of felt or other material. The lower portion

of the base has a cavity or chamber 3 centrally arranged therein from which a channel 4 extends to one of the ends of the base, the upper portion of the base having a central aperture 5 extending down to the cavity. The base has a suitable pedestal centrally thereon which preferably is made separately and comprises a foot portion 6 on which is a stem 7 having a head bar 8 thereon, the top of the bar preferably being longitudinally inclined so that its lower portion is most nearly adjacent to the end of the base that has the channel 4 therein. The pedestal has a vertical channel 9 therein 70 that is arranged to continue from the aperture 5, the foot portion 6 being secured upon the base preferably by means of bolts 10 and 10' having their heads in the cavity 3 and nuts 11 and 11' upon the foot portion. Two binding posts 12 and 13 are arranged in the cavity 3, being secured in the upper portion of the base under the foot portion 6 of the pedestal, and circuit wires 14 and 15 are connected to the binding posts 80 respectively and extend through the channel 4 in an insulator 16, the wires being connected to a suitable plug or electrical connector 17.

The oven part of the heater comprises a 85 casing 18 which preferably is cylindrical and is arranged upon the head bar 8, being inclined longitudinally and has an aperture 19 in alignment with the channel 9, and the casing is secured in place by means of a 90 clamp plate 20 arranged on the inner side of the casing and to which screws 21 and 21' are connected and extend through the head bar. The higher end of the casing has a curved head portion 22 from which an annular collar 23 extends into the casing. A head 24 is removably inserted in the opposite or lower end of the casing and is secured therein by means of screws 25, and the head preferably has a stud 26 central on its inner side. Preferably the head has a liner 27 on its inner side composed of material that will tend to prevent heat from being communicated to the head, and preferably a pin 28 is inserted in the stud. A hollow core 29 is 100 arranged in the casing at a distance from the wall thereof, one end of the core embracing the collar 23 and being centered thereby, the opposite end of the core preferably having a flared extremity 30 that is 105 seated against the liner 27, the core having suitable openings receiving the pin 28. A

heating coil 31 is suitably arranged on the core and has terminal wires 32 and 33 that extend through the channel 9 and are connected to the binding posts 12 and 13 respectively, the wires being properly insulated. Preferably the coil has a suitable covering 34 tending to prevent radiation of heat to the casing.

The cavity 3 in the base preferably has 10 a cap plate 35 therein that has side members 36 and 37 engaging the opposite sides of the cavity to retain the cap in place so as to afford a backing for the pad 2 and to close the cavity.

15 In practical use the electrical connector or plug 17 is properly connected with an electrical circuit on which an electrical current is conducted to the heater coil, resulting in the oven becoming moderately heated or sufficient for the purpose of heating curling irons or other articles which may be conveniently placed in the oven. The heater may be placed upon furniture without resulting in damage thereto, and various articles or substances may be placed upon the top of the oven to be slightly heated or warmed.

Having thus described the invention, what is claimed as new is:

- 30 1. An electrical heater including a casing having a curved head on one end thereof and an annular collar extending from the head, a head removably secured in the opposite end of the casing, a hollow core having one end elastically embracing the collar and seated on a portion of the curved head, the opposite end of the core being flared and elastically supported on the removable head, and a heater coil on the core.
- 35 2. An electrical heater including a base, a hollow pedestal secured upon the base and having a head bar on its top, a hollow casing secured to the top of the head bar of the pedestal and having an annular head in one end thereof, a head secured in the opposite end of the casing, a hollow core supported by the two heads, the core having slightly elastically connections with the heads, a heater coil on the core, and circuit wires connected with the coil and extending through the hollow pedestal.
- 40 3. An electrical heater including a casing having a head provided on its inner side with a stud having a pin secured therein, a

hollow core in the casing and having one 65 end secured to the casing and its opposite end provided with openings receiving portions of the pin, and a heater coil on the core.

4. In an electrical heater, the combination with a hollow casing having an annular head portion in one end thereof, and a head secured in the opposite end of the casing, of a base provided with a pedestal on its top having an inclined top secured to and supporting the casing in inclined position with the annular head portion higher than the opposite head, a core supported by the head and the head portion, and a heater coil on the core and having circuit wires 70 extending through the base and the pedestal.

5. In an electrical heater, the combination of a hollow core having a head secured on one end thereof with a non-conducting liner between the head and the end of the core, the opposite end of the core being open, a hollow pedestal, a casing secured upon the pedestal and having an end secured to said head, the opposite end of the casing having an annular head portion provided with a 80 collar extending into the open end of the core, and a heater coil on the core having circuit wires extending through the lower portion of the casing and through the hollow pedestal.

85 6. In an electrical heater, the combination of a base having a cavity in the lower portion thereof and a channel extending from the cavity to one end of the base, the base having also an aperture in the top thereof 90 extending to the cavity, two binding posts secured to the base and extending into the cavity, circuit wires extending through the channel and connected to the binding posts respectively, a hollow pedestal fixed upon the base above said cavity, a tubular casing secured upon the pedestal, a hollow core supported in the casing, a head connected to one end of the casing and the core, a heater coil on the core, circuit wires connected to the coil and also to the binding posts respectively and extending through the hollow pedestal and through said aperture, and a pad secured to the bottom of the base and extending over and closing said cavity.

100 In testimony whereof, I affix my signature on the 29th day of August, 1922.

AUGUST HENRY OPPERMAN.
